RANGE FINDER FOR RIFLES

Millard F. Thacker, Fort Sam Houston, Tex.

Application January 5, 1948, Serial No. 625

1 Claim. (Cl. 33—59)

1

This invention relates to a range finder adapted for attachment to telescopes and rifles.

It is an object of the present invention to provide a range finder which can be easily attached to a telescope or rifle and which includes an arm which can be adjusted or hinged to an extended position or extended to a position where it is out-of-use and parallel to the rifle barrel and wherein the adjustments for the different distances can be made along the same by sighting the gun on the target and with the other eye sighting a bead on the target, the reading being taken from the location of the particular bead which is found to coincide with the target by the opposite eye.

Other objects of the present invention are to provide a range finder which will give instantly the distance in yards to one using a rifle, which is of simple construction, easy to adjust, inexpensive to manufacture and efficient in operation.

For other objects and for a better understanding of the invention, reference may be had to the following detailed description taken in connection with the accompanying drawing, in which

Fig. 1 is a top plan view of the range finder connected to a rifle barrel.

Fig. 2 is a sectional view through the barrel and looking in elevation upon the range finder in its extended position.

Fig. 3 is a sectional and perspective view, in enlarged form, of the range finder arm and with one of the indicating elements thereon, the view being taken generally on line 3—3 of Fig. 2.

Fig. 4 is a collective view of the indicator construction.

Fig. 5 is a perspective view looking down upon the top of a rifle barrel and upon the range finder attached thereto with illustrations made thereon to indicate how the range finder is used with the rifle.

Referring now to the figures, 10 represents a rifle barrel to which my range finder, indicated generally at 11, is attached. This range finder includes separable clamping parts 12 and 13 which are shaped to fit about the sides of the barrel and to be tightened thereon by a nut 14 acting upon bolts 15. A spring 16 is provided on each bolt 15 and is disposed between the clamping parts 12 and 13. On the part 12 is a hinge formation 17 to which an arm is pivotally connected as indicated at 18. The arm is shown at 19. This arm has a scale 21 thereon and also an elongated slot 22 extending throughout the length of the arm.

On this arm there are disposed a plurality of 55 a miss.

2

indicators formed with fingers 23, each of which having a bead tip 24 at one end and an internally threaded hub 29 having flat sides 30 on the other. These indicators are locked in place on the arm 19 by a screw 25 which, as shown in Fig. 3, passes through the indicator hubs of the fingers 23 and are threaded into lock nuts 26 formed with hubs having flat sides 31 and which extend into the slot or opening 22. Each of the lock nuts 10 has a flange 28 adapted to be drawn against the face of the arm as the screw 25 is tightened. The indicators 23 can be adjusted to different distances along the arm and will indicate different distances. Accordingly, discernible targets are 15 set up at distances of 100, 200, 300, 400 and 500 yards. The indicators 23 are set up respectively on these targets.

In operation, the rifle is placed on a steady rest and the rifleman assumes the usual sighting position and takes a bead on the target, previously 20 set up at 100 yards with his left eye closed. The rifleman then closes his right eye and at the same time opens his left eye with which he will observe that the target has advanced to the left 25 along the top of the range finder. Without moving the rifle or his eyes, the rifleman reaches up with his left hand and moves an indicator 23 either to the right or to the left along the arm until the bead 24 of the indicator is exactly on 30 the target as observed by the left eye. He thereafter tightens the lock screw thus making the indicator immovable. With the target distance being at 100 yards, the rifleman will now have an indication on the arm such that he can measure 35 off a 100 yard distance. Thereafter, the rifleman will set the other indicators on other known distances. Accordingly, the indicating elements will be fixed upon the arm 19 and the range finder can now be used on targets where the distances are 40 unknown.

With the rifle and the range finder the rifleman can now determine the range of a target.

The rifle will be pointed upon the target and then the right eye will be closed and thereafter 45 the target will be observed by the left eye over the indicators. If it so happens that the target can be found in direct alignment with one of the indicators, the range will be readily determined. However, if the target does not appear exactly on 50 one of the indicators, the indicator element coming closest to the target should be used. A few yards variation would not matter because any rifle which would be used would not have enough bullet drop for such a short distance as to cause

While various changes may be made in the detail construction, it shall be understood that such changes shall be within the spirit and scope of the present invention as defined by the appended claim.

I claim:

In a range finder for firearms, the combination which comprises a mounting clamp for securing the finder to the barrel of a firearm, a range arm having an elongated slot therein and extended substantially throughout the length thereof hingedly attached to one side of the mounting clamp and positioned to extend laterally from the barrel of the firearm and also to nest against the adjacent side surface of the said barrel, a plurality of indicators including fingers having beads on one of the ends thereof and internally threaded hubs with flat sides on the opposite ends positioned on the face of the range arm with the hubs thereof extended into the slot of the arm and with the flat sides of the hubs retaining the fingers with the beads on the ends thereof extended beyond one edge of the range arm, locking screws having knurled heads threaded through the hubs of the fingers and extended into the

said slot of the range arm, and lock nuts having internally threaded hubs with flat sides and with flanges on the outer ends of the hubs positioned in the slot of the range arm with the locking screws threaded into the hubs and with the flat sides preventing turning of the nuts, the said flanges of the lock nuts coacting with the fingers for clamping the fingers against the side surface of the range arm whereby the fingers are clamped in adjusted positions by the locking screws.
